United States Patent Office

Des. 183,550
Patented Sept. 16, 1958

183,550

AUTOMOBILE

Karl Wilfert, Stuttgart-Degerloch, Germany, assignor to
Daimler-Benz Aktiengesellschaft, Stuttgart-Unterturk-
heim, Germany

Application May 4, 1956, Serial No. 41,360

Claims priority, application Germany November 18, 1955

Term of patent 7 years

(Cl. D14—3)

Figure 1 is a partial perspective view of an automobile, embodying my new design;

Figure 2 is a front view of the automobile shown in Figure 1; and

Figure 3 is a side elevation of the same automobile.

The dominant features of the automobile design in accordance with the present invention are shown in full lines in the drawing. The sides and the rear of the automobile are of conventional construction.

I claim:

The ornamental design for an automobile, substantially as shown and described.
